UNITED STATES PATENT OFFICE.

RICHARD W. MOSES, OF PITTSBURGH, PENNSYLVANIA, ASSIGNOR TO UNITED ENGINEERING AND FOUNDRY COMPANY, OF PITTSBURGH, PENNSYLVANIA, A CORPORATION OF PENNSYLVANIA.

SHEARING MECHANISM.

Application filed March 5, 1923. Serial No. 622,899.

The present invention relates to the art of metal-working, and more particularly to an improved mechanism for shearing blooms or billets delivered by a roll table.

5 In the art to which this invention relates, it is desirable to provide shearing mechanism occupying a comparatively small amount of room, whereby it is readily adapted to installation in existing mills, and 10 so arranged that it does not obstruct the ready disposition of sheared material at the delivery end of the shearing mechanism. It is also recognized that certain advantages arise from the use of an up-cut shear where- 15 by a fixed roll table may be relieved from the load imposed on the material by the shearing operation.

By the present invention, there is provided a shearing mechanism embodying the 20 foregoing desirable features and entirely obviating disadvantages inherent in down-cut shears, or shears requiring an undue amount of mill space or a specially formed roll table.

25 A preferred embodiment of the invention is illustrated in the accompanying drawings, in which—

Figure 1 is a side elevation of the shearing mechanism;

30 Figure 2 is a front elevation thereof; Figure 3 is a section on the line III—III of Figure 4;

Figure 4 is a section on the line IV—IV of Figure 3;

35 Figure 5 is a horizontal sectional view of the front housing, taken on line V—V of Figure 3; and

Figure 6 is a horizontal sectional view taken on line VI—VI of Figure 1.

40 Referring to the drawings, A represents a supporting frame for the shearing mechanism. This frame comprises a vertical housing 2 at the front end thereof and spaced vertical legs 3 at the rear end thereof. The lower end of the housing 2 is connected with the lower ends of the legs 3 by the L-shaped frame members 4. The upper ends of the legs 3 are connected with the housing 2 by the horizontal portion 5 of the frame, the latter supporting a motor 6 and the driving connections between said motor and the cutter-head slide to be hereinafter described.

45 The motor 6 drives the motor pinion shaft 7 through a suitable flexible coupling 8. The

shaft 7 is journaled in suitable bearings in 55 the frame and carries a flywheel 9 and pinion 10. The pinion 10 meshes with and drives a gear 11 mounted on a shaft 12 parallel to the shaft 7. Said shaft 12 has fixed to an end thereof a pinion 13 meshing with 60 and driving a gear 14 fixed to one end of the eccentric shaft 15.

The eccentric shaft 15 is journaled at its forward end in the housing 2 and is provided with an eccentric 16 which is operatively connected to a cutter-head 17 slidably mounted in said housing between the body portion of the latter and a face plate 18 which is spaced from said body portion by flanges 19. The body portion of the housing 70 2 has a rectangular opening 20 therein adjacent its lower end, and at the upper edge of said opening a fixed shearing member 21 is secured, said fixed shearing member cooperating with a shearing member 22 secured to the sliding cutter-head 17 to shear the material delivered by a roll table through said opening 20. The face plate 18 has an opening 23 therein for the passage of the sheared material, said face plate being provided at 75 the lower edge of said opening with a forwardly projecting apron 24 for supporting said material.

The cutter-head 17 has at its upper end an integral crosshead 25 having in its lower 85 edge a recess in which is arranged a bearing block 26 which provides a downwardly open bearing for the upper end 27 of a pitman 28. The bearing surface of said upper end 27 constitutes a portion of a cylindrical surface, and the lower end face 29 of said pitman also constitutes a portion of a cylindrical surface the axis of which coincides with the axis of the bearing surface of the upper end 27.

90 The eccentric 16 is journaled in the lower end portion of the pitman 28, and the cutter-head 17 is provided intermediate its ends with an integral crosshead 30 having an upper curved bearing surface 31, formed of 100 Babbitt metal, for cooperation with the lower end face 29 of the pitman 28.

95 Bolted to the upper end of the housing 2 is the base 32 for the hydraulic balance cylinder 33. Arranged for reciprocation in the cylinder 33 is a piston 34 having at its upper end a yoke 35 connected by rods 36 with the crosshead 25 at the upper end of the cut-

ter-head 17, said rods reciprocating through suitable openings in said base 32.

The parts 32 to 36, inclusive, constitute a hydraulic balance device of a type usually employed in this art, a constant hydraulic pressure being maintained in the cylinder 33 sufficient to substantially balance the weight of the cutter-head 17 and parts carried thereby in all positions of said cutter-head. By the provision of this balance device, the raising of the cutter-head 17 imposes substantially no load upon the motor 6 due to the weight of said cutter-head and parts carried thereby; and, after each shearing operation, said balance device permits said cutter-head to lower by gravity, but, of course, it will be evident that if the cutter-head tends to lag in the lowering operation, it will be positively moved by the eccentric 16 and pitman 28.

The mechanism above described includes a suitable clutch (not shown) for controlling the operation of the eccentric shaft 15, said clutch being operable either by means of the foot treadle 37 or either of the hand levers 38 and 39.

Referring to Figure 6, it will be seen that the shear mechanism of my invention comprises a supporting frame the base of which is substantially U-shaped in horizontal section and adapted to receive the delivery end portion of a roll table B between the sides 4 thereof, with the housing 2 which, at its lower end, connects the sides 4 of the U-shaped portion arranged directly in front of and closely adjacent to the endmost roll of the table. It will be seen, furthermore, that the shearing mechanism is supported entirely independently of the roll table without interfering with the driving mechanism

for the individual rolls and substantially entirely outside the area beneath said delivery end portion of the table, so that no portion of the shearing mechanism is subjected to the destructive action of hot scale. The shear can be installed to cooperate with an existing roll table of usual construction without interfering in any way with the operation of said table and, when so installed, occupies a minimum of mill space and leaves the delivery space in front of the shearing members substantially unobstructed by the shearing mechanism, which greatly facilitates the handling of the sheared material and the delivery thereof to cooling beds and to other points of distribution. Furthermore, all of these advantages are obtained in a shear in which the shearing load imposed upon the material by the shearing operation is not transmitted thereby to the table.

I claim:

Shearing mechanism, comprising a vertically operable shear having upper and lower blades, a roll table terminating adjacent the blades and adapted for delivering material to the shear, the lower shear blade being adapted for upward movement and normally lying below the level of the roll table, crank means for operating the movable shear blade, a shaft for said crank means mounted above the roll table and extending along the line of travel of material on the handling means, and a motor for driving the shaft, the motor being also mounted over the roll table, substantially as described.

In testimony whereof I have hereunto set my hand.

RICHARD W. MOSES.
